UNITED STATES PATENT OFFICE.

OSKAR WARTEMANN, OF NEW YORK, N. Y.

BUILDING DAMS.

1,133,768.

Specification of Letters Patent.

Patented Mar. 30, 1915.

Application filed July 1, 1914. Serial No. 848,509.

To all whom it may concern:

Be it known that I, OSKAR WARTEMANN, a citizen of the United States, and a resident of New York city, College Point, in the county of Queens and State of New York, have invented certain new and useful Improvements in Building Dams, of which the following is a specification.

This invention relates to improvements in building dams in running streams of water and the object of my invention is to devise a new and improved method of building such dams in an economical manner without diverting the entire stream.

In the accompanying drawings in which like numerals of reference indicate like parts in all the figures:—Figure 1 is a plan view showing part of a stream and one half of the dam constructed according to my new and improved method. Fig. 2 is a similar view showing the means for constructing the other half of the dam.

The dam may be made of reinforced concrete, masonry, brick, wood or any other suitable material. For the purpose of building a dam, I first erect a coffer dam 1, preferably composed of spiles 2, driven into the river bottom and provided with two covering layers 3 of planks and if necessary provided with an intermediate plank layer 4 and fill in the space with gravel or a mixture of gravel and cement. This coffer dam 1 begins at one shore of the stream and extends down stream at an angle of about 45 degrees substantially to the center of the stream at a point on a line transversely to the stream at the up stream face of the proposed dam. The land end of the coffer dam will thus be a certain distance up stream from the location of the permanent dam. At the inner or stream end of the coffer dam which as stated is approximately at the center of the stream, I construct a coffer dam 6 in the manner previously described, said coffer dam 6 extending longitudinally down stream and being connected with the stream end of the coffer dam 1. The central coffer dam 6 can extend down stream a greater or less distance, this depending of course to a greater or less extent upon the depth of the stream and the down grade of the bottom of the stream. The water from above the coffer dam flows off through the space between the central dam 6 and the shore opposite the one with which the dam 1 is connected as the dam 6 is carried down

stream a considerable distance so that no water can back up the space bounded by the dams 1 and 6 and thus the shore from which the coffer dam 1 extends will be comparatively dry and if there are any low places the water is pumped out so that in the above defined space, foundations, trenches and so forth can be dug for the permanent transverse dam. Then the necessary excavations are made and a section 10 of the dam is built to extend from the shore or a greater or less distance in-shore to the center of the stream, that is to the longitudinal section of the coffer dam 6. This dam 10 may be made of concrete, reinforced concrete, stone, masonry, brick, or any other suitable material as the circumstances may require. Embedded in said dam, are a series of tubes 11 located at the bottom of the river or stream and leading from the up stream side of the dam to the down stream side and these tubes are each provided with a shut off gate or valve 12 of any suitable construction or type. The combined area of the several tubes 11 is of such size as to be able to carry off the normal flow of water in the stream at the time that the dam is being constructed. After one half of the dam has been constructed in the manner described, the coffer dam is removed, the diagonal section 1 as well as the longitudinal section 6. Then a similar dam 13 is built from the opposite shore toward the free end of the completed dam, also at an angle of about 45 degrees down stream. This dam 13 extends a greater or less distance from the proposed dam, up stream, diagonally toward the free end of the completed section of the dam and meets the completed dam section 10 a short distance from the free end of the same. On the down stream side of the completed section of the dam, a longitudinal coffer dam 14 is constructed from the free end of the completed section of the dam down stream. The gates 12 of the tubes 11 are then all opened so that all the water in the stream can flow through the tubes 11, thus relieving the coffer dams to a very great extent and the space between the coffer dams and the shore is now dry and the dam is completed in this space to the other shore as shown in the drawings and after the dam has been fully completed, the coffer dam sections 13 and 14 are removed. In case the water is to be impounded, the gates 12 of the tubes 11 are closed so

that the water can rise in the basin formed at the up stream side of the dam until it flows over the top of the dam, but if such overflow is not desired, the gates 12 and 13 can be opened in the usual way.

In mountain streams, having rocky shores, it is too expensive to divert the stream for the purpose of building a dam, as the current of these streams even in so-called dry seasons, when the quantity of water is very small, is so great as to render it absolutely impossible to construct a foundation for the dam under water and therefore it is necessary that the water shall be excluded entirely from the site of the dam. Furthermore when one half of the dam is completed an outflow for the water from above the dam must be provided as otherwise the remaining half of the bed could not be put in condition for building the foundation of the dam and the structure of the dam itself. In order to prevent undue accumulation of water on the up stream side of the dam and the up stream part of the coffer dam, it is essential that the water shall be removed directly above the bottom of the stream and not at any elevation above the same so as to subject the newly made dam and the coffer dam to as little pressure as possible, always bearing in mind, that the current is very great in these mountain streams. This method of course is to be employed in streams having considerable declivity as compared with sluggish streams as otherwise the water would be apt to rush in behind the dam 6 and that of course would defeat the very object of my invention.

I am aware that dams have been provided with the relief valves and I am also aware that coffer dams have been used in the construction of permanent dams.

Having described my invention what I

claim as new and desire to secure by Letters Patent is:—

The herein described method of constructing a dam across a water way consisting in first constructing a longitudinal coffer dam in the stream between the shores and connecting it with a coffer dam extending from one end of the longitudinal coffer dam up stream to one shore at an angle of about 45 degrees thereby forming a well which is bounded by one shore, the diagonal part of the coffer dam and the longitudinal part of the coffer dam and is open down stream, 55 erecting a dam within the space thus bounded by the coffer dams and shore, providing outlet tubes in the dam thus formed directly above the bed of the stream, removing the diagonal coffer dam section, constructing a 60 coffer dam from the free end of the completed half of the dam up stream at an angle of about 45 degrees to the shore opposite the one to which the first inclined coffer dam section extended, erecting a coffer dam from 65 the down stream side of the completed section of the permanent dam at the free end of said dam, which coffer dam section extends down stream thus forming a space bounded by the last two mentioned coffer 70 dams and a shore, which space is open at the down stream side and constructing the remaining part of the permanent dam in the space thus bounded by the said coffer dams and shore and then removing all the 75 remaining coffer dams, substantially as set forth.

Signed at College Point, in the county of Queens and State of New York this 16th day of February A. D. 1914.

OSKAR WARTEMAN.
